(57) **CLAIM**

The ornamental design for a hand-held vacuum cleaner, as shown and described.

DESCRIPTION

1. Hand-held vacuum cleaner

1.1 : Front

1.2 : Back

1.3 : Left

1.4 : Right

1.5 : Top

1.6 : Bottom

1.7 : Perspective

1.8 : Perspective

Reproduction 1.1 is a perspective view of a hand-held vacuum cleaner showing our new design;

Reproduction 1.2 is another perspective view thereof;

Reproduction 1.3 is a front view thereof;

Reproduction 1.4 is a back view thereof;

Reproduction 1.5 is a left view thereof;

Reproduction 1.6 is a right view thereof;

Reproduction 1.7 is at top view thereof; and

Reproduction 1.8 is a bottom view thereof.
